UNITED STATES PATENT OFFICE.

FREDERICK G. SIMPSON, OF SEATTLE, WASHINGTON.

MICROMAGNETIC DETECTOR.

1,211,770.

Specification of Letters Patent.

Patented Jan. 9, 1917.

Original application filed November 1, 1912, Serial No. 729,064. Divided and this application filed April 23, 1913. Serial No. 763,143.

To all whom it may concern:

Be it known that I, FREDERICK G. SIMPSON, a citizen of the United States, residing at Seattle, in the county of King and State 5 of Washington, have invented certain new and useful Improvements in Micromagnetic Detectors, of which the following is a specification.

This application is a division of one filed 0 by me Nov. 1, 1912, Serial No. 729,064.

The invention herein disclosed relates to certain improvements in micro-magnetic apparatus for the reception of signals of the Hertzian wave type.

15 The present invention has for its object the provision of a new and improved means for detecting the existence of voltages or currents in a wireless telegraph receiving circuit which have been generated within 20 such a circuit by the passage of a wave train of Hertzian waves.

25 A further object of the invention is the provision of instrumentalities which may be selectively tuned for the reception of Hertzian wave trains arriving at a certain definite rate per second, thereby preventing interference from wave trains arriving at the receiving station at rates other than that adjusted for.

30 To this end the invention consists in the structure of parts and in the combination thereof for the purpose specified substantially as hereinafter set forth and claimed.

In the accompanying drawings, which 35 form a part of this specification, Figure 1 is a view partly in side elevation and partly in longitudinal section of a receiving instrument for wireless telegraph systems. Fig. 2 represents a horizontal section of the same.

40 Fig. 3 is an enlarged transverse section through magnet 17, Fig. 1. Fig. 4 is a transverse vertical section through the instrument. Fig. 5 is an enlarged fragmentary vertical section of one of the slide members. Fig. 6 is a plan view thereof. Fig. 7 is a diagrammatic view illustrating the application of the instrument to a wireless telegraph receiving circuit.

45 Members 1' and 1'', made of brass or other suitable material, are coupled at one end by a base element 2' and at the other end by a plate 42 which is supported upon

base 2''. The members 1' and 1'' are both slotted as shown, to accommodate a magnet carriage 26, which may be used interchangeably with either of them.

55 23 is a core for the electro-magnet coil 24 wound on a bobbin or spool 25, the terminals of which are carried to the binding posts 29. This core is threaded through the carriage 26 and the carriage is engaged by a nut 27 whereby the carriage may be clamped to either of said members. A block 21, of insulating material, is supported by the members 1' and 1''. This block supports, 60 through the medium of the depending insulating blocks 22' and 22'', a coil of fine wire 17 which is wound about a core 18, consisting of a number of fine iron wires, each wire being insulated from the others, Fig. 3. 70 The block 21 also supports, through the medium of an arm 20, the solenoid 19 which is wound upon the spool 20'. The windings of the magnet coil 17, and the solenoid 19, are usually connected in series with each 75 other, the terminals, as shown in Fig. 4 being carried to binding posts mounted on the block 21.

80 30' and 30'' represent reeds or bands of thin steel, or other magnetizable material, of approximately twelve one-hundredths of an inch in width and three one-thousandths of an inch in thickness. The corresponding end of each reed is fastened by the clips 33 to a pulley 31 of insulation. The other extremities are fastened to metallic blocks 6 fitted in the metallic bushings 7. The blocks 6 are threaded by screws 9 and are adapted to have a short longitudinal movement regulated by the screws. In the vicinity of its 90 middle, the reed 30'' has rigidly connected therewith a pin 16'', which is constructed of aluminum or other suitable conducting material. To reed 30' there is also connected a like pin 16' in alinement with pin 16''. 95 On the inner end of pin 16'' is mounted a small globule of gold, platinum or other non-oxidizing conducting material indicated at a, while on the end of pin 16' is mounted a small block b of carbon. The point of contact between the elements a and b is capable of microphonic adjustment.

100 Reed 30' passes loosely through the bobbin 20' of solenoid 19. The core 18 of coil

17 is placed to permit of an air gap, approximately one thirty-second of an inch, between its ends and the respective reeds 30' and 30''. The pulley 31 is journaled on 5 shaft 32 which is rigidly connected to a cylinder 34. This cylinder is fitted to move longitudinally in a stationary ring 40' having arms 40 which are rigid with members 1' and 1''. Mounted within the cylinder is a 10 compression spring 35, through the axis of which passes the stem of the screw 48, which also passes through washer 43, the end plate 42, a washer 36, and threads into nut 37. This nut is provided with pins which extend 15 into slots provided in the cylinder 34, thereby preventing the nut from turning. The cylinder 34 and the ring 40' are respectively provided with a key way and key 41, which prevents the cylinder from turning in the 20 ring. By means of screw 48, the spring 35 may be adjusted to communicate, through the medium of cylinder 34, shaft 32 and pulley 31, tension to the reeds 30' and 30''. Individual adjustment of the reeds may be 25 had through blocks 6 and screws 9.

Knife-edge pieces 14, made of ivory or other insulation, are rigidly fastened to the holders 15 which, in turn, are fitted to slide upon the carriage bodies 11. The latter are 30 each fitted at their ends to slide longitudinally upon the members 1' and 1'', being held in place by attachments 12. Bushings 45 are retained by and between the carriage parts 11 and 12 and are respectively threaded by the right and left screw 44, which is borne at one end by the base 2'', passing through base 2' at the other end, and being held in place by journal-cap 49, as indicated in Fig. 1. The holders 15 for the knife-edge 35 pieces 14 can be made to approach to and recede from each other in pairs, by means of the right and left screws 13. It is to be noted that two assemblages of parts, herein-after called "sliders," and each made up of 40 the parts 11, 12, 13, 14, 15 and 45, are arranged to move in longitudinal direction, approaching to or receding from each other, by means of the screw 44; while the reeds 30' and 30'' can be adjusted in a limited degree as to their distance from each other by 45 means of the screws 13, controlling the position of the knife-edge pieces 14, which bear against them.

Referring now to Fig. 7, 52 is a receiving 50 antenna. 51 is a variable inductive coupling having a primary 51^p and a secondary 51^s. The antenna is grounded through the primary. Hertzian wave trains arriving at the antenna induce voltages therein, which cause 55 high frequency oscillating currents to flow through the antenna and the primary to and from the earth. These currents, by inductive action through the inductive coupling 51, produce voltages within the secondary 60 circuit, consisting of the secondary coil 51^s,

the condenser 53, the solenoid coil 19 and the electro-magnet coil 17.

Reed 30' lies within the magnetic field of the electro-magnet coil 24, wound about core 23. This magnet is excited by current from 70 the battery 56. The voltage at the terminal of coil 24 is capable of adjustment through the medium of the regulating rheostat 55. The density of the magnetic field in the vicinity of 30' can be regulated by variation 75 of the exciting current, and also by movement of the core 23. Oscillating currents of high frequency flow through coils 19 and 17, producing motion in reeds 30' and 30''. In the absence of these oscillating currents, the 80 reed 30' is moved slightly away from its position of normal rest by the magnetic attraction of the core 23 of the electro-magnet 24, and a state of magnetic polarity exists in said reed at a point opposite the core. 85 Magnetism is also communicated to a lesser degree to core 18 of coil 17. Upon the arrival of a series of Hertzian waves, high frequency oscillating currents flow through coils 19 and 17, which in effect partially 90 suppress the magnetic condition of the reed 30' and the core 18, respectively, permitting the reed because of mechanical tension thereon to recede slightly from the magnet core 95 23. At the same instant the high frequency currents flowing through coil 17 induce within the core 18 an oscillating magnetic flux, which has an integrating tendency to attract reeds 30' and 30'' to its extremities. The phenomena described are simultaneous 100 in their action and have a tendency to draw reeds 30' and 30'' closer together, thereby decreasing resistance at the microphonic contacts *a* and *b*, which permits an increased 105 flow of current from the generator 57 through the reed 30', pin 16', carbon element *b*, gold element *a*, pin 16'', reed 30'' and galvanometer 60, or other suitable indicating or signaling instrument.

As each series of Hertzian waves communicates but a single impulse to the reeds 30' and 30'', each reed will, if properly proportioned, vibrate at the frequency of the wave trains, *i. e.*, at the same rate per second of vibrations as is the rate per second in the 110 number of wave trains arriving at the receiving station. This phenomenon is due, as shown herein, to the cumulative effect of the high frequency alternating voltages or currents produced by each Hertzian wave train. 115 For the purpose of securing the greatest possible efficiency in the operation of the micro-magnetic detector, it is necessary that the vibrating reeds shall be so proportioned as to dimensions, in accordance with the principle in acoustics, that their so called natural period of vibration shall be the same as the frequency of the incoming Hertzian 120 wave trains. Assuming now that it be desired to receive signals from a transmitting 125 130

station sending forth wave trains at a rate of 1000 per second, while wave trains of the same wave length are being sent forth by another transmitting station at a rate of 120 per second, without interference; the micro-magnetic detector being previously adjusted to respond to a frequency of 120 impulses per second. This result can be accomplished by either increasing the tension on reeds 30' and 30" by means of the screw 39, or by drawing the sliders closer together by means of the screw 44, or by means of both. The active lengths of the reeds, lying between the sliders, can be so adjusted as to respond to a frequency of impulses of 1000 per second even though there may be impulses at other rates per second at the same time communicated to them.

It can be readily seen, therefore, that the micro-magnetic detector described herein, may be so constructed as to be capable of adjustment for vibration of its reeds by varying the active length thereof, or the tension thereon, so that they will respond by vibrating to impulses communicated to them as hereinabove described by Hertzian wave trains arriving at a preselected frequency, and that Hertzian wave trains arriving at any other frequency than that adjusted for, will not produce such vibrations, and therefore will not interfere with the vibrations produced by the wave trains arriving at the frequency adjusted for. This property of the micro-magnetic detector herein described should not be confounded with the adjustment for electrical resonance by properly portioning the capacity and inductance in the receiving circuit or circuits, which adjustment is entirely electrical and is made for the frequency of the oscillations within the wave trains themselves, or in other words, for the wave length of the Hertzian waves. The adjustment in the micro-magnetic detector is made to the frequency of the wave trains, and is entirely mechanical in its nature.

The invention claimed is:—

1. In a wireless telegraph system, the combination with two suitably supported magnetizable reeds disposed at a suitable distance from and parallel with each other, of means for changing the natural and fundamental rate of vibration of each of said reeds, means for magnetically polarizing to a desired constant degree one of said reeds, an electro-magnet disposed to extend lengthwise between said reeds, and adapted to be energized to attract said reeds each toward the other, a helix of insulated wire disposed to surround one of said reeds whereby electrical energy may be caused to change the magnetic condition of said reed, and a pair of movable electrical contact points associated with and adapted to be controlled by said reeds.

2. In a receiving apparatus of a wireless telegraph system, the combination with two magnetizable members suitably supported to adapt them to vibrate, of independent means for magnetizing one of said members to a desired normal degree, electro-magnetic means adapted to change the said normal degree of magnetization, an electro-magnet disposed to adapt it to operate to change the distance between the movable portions of said members, two electrical contact points associated with the movable portions of said members and adapted to be actuated thereby to vary the electrical resistance of their contact, and means for adjusting each of said members to have a desired natural and fundamental rate of vibration.

3. In a receiving apparatus of a wireless telegraph system, the combination with a suitable supporting frame, of a shaft mounted to rotate in bearings within said frame, equal portions of said shaft being provided one with a left-handed and the other with a right-handed screw thread, carriers adapted to be moved in guide ways disposed within said frame, one of said carriers being provided with a left-handed screw thread which is disposed to engage with the left-handed screw thread of said shaft while the other of said carriers is provided with a right-handed screw thread and disposed to engage the right-handed screw thread of said shaft, whereby said carriers are adapted to approach toward and recede from each other in response to a rotation in a proper direction of said shaft, two reeds of magnetizable material each of which is stretched between adjustable supports that are adapted to vary their tension, said reeds being disposed parallel with each other and parallel with the path traveled by said carriers, projecting arms fixed in each of said carriers and disposed to engage with and press against said reeds whereby, when said carriers are moved toward each other and away from each other, the active length of said reeds may be changed, and adjustable movable electro-magnetic means for changing the magnetic conditions of said reeds.

4. In a micro-magnetic receiving instrument, the combination of adjacent vibrating reeds, engaging microphonic contacts carried by said reeds, means for varying the length of the vibratory portions of said reeds, means for magnetizing one of said reeds, an electro-magnet located between the reeds for attracting them, and an adjustable electro-magnet whose field includes the magnetized reed and the core of said first electro-magnet.

5. In a micro-magnetic receiving instrument, the combination of a vibratory reed, a magnetizing helix surrounding it, microphonic contacts actuated by said reed, an electro-magnet for attracting said reed in

- one direction, and a second electro-magnet for attracting said reed in the opposite direction, the coil of the second magnet being in series circuit with said helix and having 5 its core in the field of the first magnet and composed of fine individually insulated iron wires.
6. In a micro-magnetic receiving instrument, the combination of a supporting 10 frame, vibratory reeds stretched therein, engaging microphonic contacts carried by said reeds, devices for individually adjusting said reeds, a device for simultaneously adjusting the tension of said reeds, carriers movably 15 mounted in said frame and having arms for engaging said reeds, adjusting means for varying the distance between said carriers, adjusting means for varying the distance between said arms upon each carrier, and electro-magnetic means for actuating said vibratory reeds.
7. In a micro-magnetic receiving instrument, the combination of a supporting 20 frame, vibratory reeds stretched therein, engaging microphonic contacts carried by said reeds, devices for individually adjusting said reeds, a device for simultaneously adjusting the tension of said reeds, carriers movably mounted in said frame and having arms for 25 engaging said reeds, adjusting means for varying the distance between said carriers, adjusting means for varying the distance between said arms upon each carrier, electro-magnetic means for attracting said vibratory reeds toward each other, and an 30 electro-magnet mounted in said frame for adjustment lengthwise of said reeds and having a core adjustable toward and from one of said reeds.
- 40 8. In a receiving apparatus for wireless telegraph systems, a magnetizable element capable of directly responding to particular Hertzian wave trains by means of magnetic fields produced adjacent to, and one of which 45 surrounds a portion of, said element when said wave trains exist in a wireless receiving circuit.
9. In a receiving apparatus for wireless 50 telegraph systems, a magnetizable and vibratable element disposed within a helix, and means to produce a magnetic field adjacent to said element, the helix and the means coöperating with said element to
- cause the element to immediately and resonantly respond to the frequencies of a Hertzian wave train directly impressed thereon. 55
10. In a receiving apparatus for wireless telegraph systems, a vibrator member capable of having Hertzian wave trains periodically and directly impressed thereon to produce a maximum vibration of the member when the frequency of the wave train in a wireless receiving circuit is the same as the frequency of the element, through the medium of separate and distinct magnetic fields 60 produced adjacent thereto, one of said fields produced adjacent thereto, one of said fields surrounding a portion of said member. 65
11. In a receiving apparatus for wireless telegraph systems, a flexible and magnetizable member capable of directly responding by maximum vibration to Hertzian wave trains having a like definite frequency of vibration on their passage through a wireless receiving circuit, including electromagnetic means adapted to produce magnetic fields adjacent to said member, one of said means surrounding a portion of said member. 70
12. In a receiving apparatus for wireless telegraph systems, a magnetizable element 75 capable of directly responding by maximum vibration to Hertzian wave trains having a corresponding frequency when the trains are impressed on a wireless receiving circuit including a helix surrounding a portion of 80 said element.
13. In a receiving apparatus for wireless telegraph systems, a flexible element having an adjustable period of vibration and capable of magnetization and demagnetization 85 to vary the hysteresis effect by means of magnetic fields produced adjacent to, one of which surrounds a portion of, said element, said fields being produced by the action of directly impressed electromagnetic 90 wave trains arriving at definite speed to produce the maximum vibration of the element when adjusted to respond to the wave train frequency. 95

Signed at Seattle, Wash., this 15th day of April 1913.
